Van Emmer Fish & McDonald

UNITED STATES PATENT OFFICE.

ANDREW F. CURTIN, OF MEDFORD, MASSACHUSETTS.

OUTLET-VALVE-OPERATING MECHANISM FOR FLUSHING TANKS.

Application filed May 20, 1919. Serial No. 298,451.

To all whom it may concern:

Be it known that I, ANDREW F. CURTIN, a citizen of the United States, residing at Medford, in the county of Middlesex and 5 State of Massachusetts, have invented certain new and useful Improvements in Outlet-Valve-Operating Mechanism for Flushing Tanks; and I do hereby declare the following to be a full, clear, and exact description of the invention, such as will enable others skilled in the art to which it appertains to make and use the same.

This invention relates to a valve operating mechanism and particularly to an outlet 15 valve operating mechanism for flushing tanks.

The invention has for an object to provide a valve operating mechanism of improved construction possessing positive action and 20 increased durability and life.

Another object of the invention is to provide a valve operating mechanism whose individual elements cooperate to prevent disengagement thereof after the mechanism has 25 been assembled.

With these objects in view, the invention consists of the valve operating mechanism hereinafter described and particularly defined in the claims.

30 In the drawings illustrating the preferred embodiment of the invention, Figure 1 is a rear elevation; Fig. 2 a plan; and Fig. 3 a front elevation of the improved valve operating mechanism.

35 The valve operating mechanism illustrated in the drawings, is described as follows: A relatively long operating lever 10 is pivotally mounted at a point intermediate the ends thereof, upon a stud 12 laterally 40 extended from a supporting arm 13. The latter is provided with a square boss 14 adapted to fit into a recess in the side wall of a flushing tank, and is firmly secured in the wall of the tank by a hollow bolt 15 having a stem 16 which passes through the 45 wall of the tank and screws into the boss 14 of the supporting arm 13. A wire or chain 17 connects one end 18 of the operating lever 10 with the outlet valve of the flushing 50 tank, so that when the end 18 is raised the outlet valve is opened to permit water to flow from the tank to perform the flushing operation. The construction and operation of the outlet valve may be of any usual or 55 preferred form.

The operating lever 10 is constructed so

that one end 19 is thicker and heavier than the other end 18, and forms a counter weight tending to depress the end 19 and to raise the end 18. The end 19 is provided with a 60 double curved bearing surface 20 with which a crank pin 21 is adapted to cooperate to cause depression of the end 19 whenever the crank pin 21 is moved laterally in either direction. The crank pin 21 is extended from a crank 22, which is provided with a shaft 23 extending through the hollow bolt 15 and in which it is rotatably supported. A handle 25 is secured to the outer end of shaft 23 by a set screw 26. A lug 27 extended 70 outwardly and upwardly from the supporting arm 13 serves the purpose of limiting the downward swing of the operating lever 10, and also to retain the same on its pivot 12 within certain limits of its oscillation 75 thereon.

In assembling the valve operating mechanism and installing the same in its operating position in the flushing tank, the operating lever 10 is slipped onto the pivot 12 80 while in a position substantially perpendicular to the supporting arm 13 (see dotted lines Fig. 1). The operating lever 10 is then swung into a substantially horizontal position, being arrested in its movement by 85 contact with the lug 27. The shaft 23 of the crank 22 is then inserted through the supporting arm 13, thus bringing the crank pin 21 in a position directly above the bearing surface 20 of the operating lever 10. 90 It will be observed that the assembling operation as thus far described may be conveniently done before the supporting arm 13 is secured to the tank. The partially assembled mechanism is then installed in the 95 tank by inserting the shaft 23 through a hole in the wall thereof and screwing the bolt 16 into the boss 14 until the nut 15 bears against the outer side of the wall of the flushing tank, the usual rubber washers 100 being employed outside and inside of the tank. The handle 25 is then slipped over the end of the shaft 23 and is secured thereon by the set screw 26, thus locking all the parts in their operative positions. The wire 105 or chain 17 is then attached to the end 18 of the operating lever 10, and the valve operating mechanism is completely assembled.

It will be observed that the construction of the valve operating mechanism is such 110 that it may be very easily installed in the flushing tank, and that after it has been

installed in the tank, the various elements thereof are locked in their relative operating positions so that there is nothing which can get out of working order.

5 While the preferred embodiment of the invention has been described and illustrated, it is to be understood that it may be embodied in other forms within the scope of the following claims.

10 I claim:

1. An outlet valve operating mechanism for flushing tanks, comprising a supporting arm secured to the wall of the tank, an operating lever pivoted thereon, a crank pivotally mounted on the supporting arm provided with a crank pin adapted to engage and actuate the operating lever and arranged to limit its oscillation in one direction, said arm being provided with a stop 15 which limits the oscillation of the operating lever in the opposite direction, a lug supported to engage the operating lever in all positions within the limits of its turning movements permitted by the crank and stop, 20 the operating lever being removable by first removing the crank and then swinging the lever to a position beyond the lug.
2. An outlet valve operating mechanism

for flushing tanks, comprising a supporting arm secured to the wall of the flushing tank 30 provided with a stud laterally extended from the arm, an operating lever pivotally mounted on the stud, a lug mounted on the arm and limiting the oscillation of the operating lever in one direction, a crank pivotally mounted on the arm for operating the lever and constituting a stop limiting the oscillation of the operating lever away from the lug, said lug being provided with a portion 35 to engage the lever and hold it from movement lengthwise of the stud within the limits of oscillation permitted by the lug and crank.

3. An outlet valve operating mechanism for flushing tanks, comprising a valve operating lever, a pivot upon which it is supported, a pin for operating the lever and limiting its movement in one direction, a stop for limiting its movement in the opposite direction, means for preventing movement of the lever lengthwise of its pivot within the amplitude of movement permitted by the pin and stop, and permitting such movement beyond the limit of throw of the lever determined by the pin.

ANDREW F. CURTIN.
